UNITED STATES PATENT OFFICE.

ALFRED CORDINGLY, OF DENVER, COLORADO.

CAR-WHEEL MOLDING AND CASTING FLASK.

1,003,709.

Specification of Letters Patent. Patented Sept. 19, 1911.

Application filed March 4, 1911. Serial No. 612,302.

To all whom it may concern:

Be it known that I, ALFRED CORDINGLY, a citizen of the United States of America, residing in the city and county of Denver 5 and State of Colorado, have invented a new and useful Car-Wheel Molding and Casting Flask, of which the following is a specification.

My invention relates to improvements in car wheel molding and casting flasks, and the objects of my invention are: First—to provide a sectional molding flask, the parts of which will accurately center themselves when put together, no matter how roughly the flask is handled, and that is adapted to make a mold that will cast any kind or character of a wheel accurately and that will permit wheels to be accurately duplicated in any desired number. Second— 10 to provide a wheel molding flask that will permit one part of a wheel to be made by one molder in one part of a foundry, and the other part of the mold to be made by another molder in another part of a foundry or at a distance from and independent 15 of the molder molding the first part, and that is so arranged that the two parts of the molded flask can be quickly put together, and so arranged that the cover 20 pieces of the pattern are accurately and quickly centered; and third—to provide a two part wheel molding and casting flask that is provided with a tread chilling ring portion that is removable from the cope or upper section of the flask when cracked or 25 warped or otherwise worn out of proper form and is arranged to permit a new tread chilling ring to be replaced on the cope and thus prevent the throwing away of the 30 whole cope or top section when a chilling ring is worn out.

I attain these objects by the mechanism illustrated in the accompanying drawings, in which:

Figure 1 is a plan view of the nowel ring with the wheel pattern therein. Fig. 2 is a central, vertical, sectional view through the nowel ring and wheel pattern, showing sand which has been tamped in the ring 45 and around the pattern to form the lower half of the mold. Fig. 3 is a perspective view, showing the nowel ring in a reversed position to that shown in Figs. 1 and 2, the wheel pattern having been withdrawn 50 from the sand, leaving the completed lower half of the mold. Fig. 4 is a vertical, sec-

tional view through the cope or upper flask section and the master pattern by which the upper half of the mold is formed, the portion of the cope above the master pattern being filled with sand which surrounds the upper part of the master pattern, a hub pattern and a pouring core which rests upon the hub pattern. Fig. 5 is a side elevation of the flask comprising the cope and nowel ring, these parts being clamped together by the usual clamping hooks. Fig. 6 is a vertical, sectional view through the flask showing the completed mold ready to receive the molten metal. Fig. 7 is a plan view on a reduced scale of the cope; and Fig. 8 is a plan view of the gage for centering the core which forms the bore of the hub.

Similar letters of reference refer to similar parts throughout the several views.

Referring to the drawings, the numeral 1 designates the setting plate of my improved mold. This setting plate comprises any suitable flat smooth topped plate of 80 wood or metal, the bottom of which is provided with ribs 2, in order to strengthen and keep it from working as well as to raise its top surface far enough above the bottoms of the ribs to enable a molder to place 85 his hands under it and lift it around. Upon this setting plate I lay the wheel pattern, which is divided into two parts, the hub 3 and spokes 4, which are made in one pattern, and the tread 5 and flange 6, which 90 are made in a separate pattern, which is in the form of a ring, into which the spokes and hub fit. The tread portion 5 is preferably made of wood, although if desired it may be made of any other suitable material, and the flange 6 is preferably made of cast iron but it may be made of any other suitable metal or material. The tread 95 5 is preferably built up of three layers of boards, each layer being formed of pieces 100 of boards secured together, with the grain of each piece arranged at a different angle to the grain of the other pieces. This ring pattern is machine finished on its inside and top surfaces, and on top of this ring pattern I place a ring 7, which I term the drag or nowel ring. This drag or nowel ring is made of cast iron. This nowel or drag ring comprises a ring band portion 8, provided with enlarged flanges 9 and 10 at the opposite ends of the band portion, and it is provided with four upwardly projecting lugs 110

9^A, although more or less can be used if desired. Both the upper and lower faces of this drag ring are machined flat and smooth across to the lugs. The inner faces are also 5 machined by being bored to a predetermined size that is adapted to fit the lower edge of the cope or upper part of the mold, as will be explained more fully hereinafter. The inner surfaces of these lugs are, however, bored to have an outward diverging taper of sufficient outward pitch to permit the lower end of the cope to be free and loose between these lugs when it is first entered between them and to center closer as 10 it is lowered between them and to fit against them when lowered down on top of the turned surface of the drag ring, thus insuring that the cope or top section of the mold will always lower centrally and fit 15 exactly concentric with the drag or nowel ring. The drag ring is then filled with sand, which is tamped between the spokes around the hub and over the pattern up even with the top of the drag ring, in an 20 operative molding manner. This drag ring, the flange ring of the wheel pattern, and the setting plate I term the lower part of my improved double wheel molding flask. This lower half of the flask with the wheel 25 pattern still molded up within it is then turned upside down and is placed on top of a cast iron ring plate 11, which I term the bottom plate, the plate 11 having first been placed upon the top of the drag ring to hold the sand within the same.

The separate ring flange part 6 of the wheel pattern is then drawn from the mold, and afterward the hub and spokes are withdrawn from the mold, leaving the drag ring 40 on the plate with the mold of the wheel built up above it, as shown in Fig. 3, in which the hub space 12 and spoke spaces 13 and the wall that forms the inner peripheral wall of the wheel are shown. This 45 completes what I term the lower half of the mold. The perforated ring plate upon which the drag ring rests consists of a ring shaped lower ring portion 14, that rests on the ground or floor of the foundry and a flat plate portion 15 that is formed on one 50 end of the ring portion and is preferably of enough larger diameter to form a lifting and clamping edge portion around it for the hands of an operator and the ends of 55 the clamping dogs 16. This plate is of the same or about the same size of the flange ends of the drag ring. This lower part or section of my improved two-part wheel casting flask is as illustrated in an operative 60 molded condition, and is ready for the cope or upper section portion of the mold, which is provided with a mold of a pattern 17, which I term a master wheel. This master wheel pattern is made of cast iron and 65 is partially machine finished, as will be de-

scribed hereinafter. This master wheel comprises a hollow base ring portion 18, which is provided with a base edge flange 19. This base ring portion is provided with a top plate portion 20, which projects in 70 a top flange portion 21 over the top edge of the ring. At the outer edges of the plate portion and on the sides of the base ring guide centering lugs 22 are formed. These lugs are placed at equidistances apart 75 and as many may be used as desired. I preferably use four of these lugs, and they are arranged to extend vertically upward above the top plate a few inches, and the inner surfaces are bored out concentrically 80 with the axial center of the disk portion of the master pattern and they are tapered divergingly outward from the top plate to the upper ends sufficiently to give a clearance space or an enlarged diameter between 85 them at their upper ends of about from three-eighths to a half inch. This tapering clearance space between the lugs is provided to permit the lower edge of the cope or top section of the flask 23 to enter loosely 90 between the lugs and center as it is lowered into bearing contact with the bore of the lugs at their junction with the machined surface of the master pattern.

From the center of the top plate and base ring a round disk portion 24 projects upward a distance equal to the width of the tread portion of the flange of the wheel that is to be cast and the peripheral edge of this disk forms the outer wall of the mold's 95 boundary or the outer peripheral wall of the wheel that is to be cast.

A slight circular depression is formed in the top surface of the disk portion of the master wheel pattern, which leaves a slightly 105 raised top rim flange 25 on the top peripheral edge of the disk.

A short center pin 26 is formed in the axial center of the top of the disk portion of the master wheel which enters the centering pin aperture 27 of a pattern 27^A of the hub portion of a wheel, while the base portion of the hub rests loosely on the top surface of the wheel. This hub pattern may be of any size or length. The top surface also 110 and the vertical side of the disk, as well as the top of the plate portion of the base ring, is also machine finished up to and against the centering lugs. This master pattern is used to produce the mold of the outer portion of the hub of the wheel and a portion of the tread and to center this hub in the center of the chill surface of the cope or upper section 23, and it is used as follows: This master pattern is positioned in a level 115 position on a suitable table or bench or on the floor, and the top cope or upper section of the mold is placed over it. This cope or top section 23 contains in its construction and arrangement one of the most essential 120

features of my invention. This cope or upper part of the flask comprises a round ring-shaped casting 29 that contains two elements, one of which is a central cylindrical sleeve portion 30 that is positioned in the center of the ring by radial arms 31 that extend from the inner peripheral wall of the ring to this cylindrical sleeve portion and which, together with the cylindrical sleeve, are cast integral with the ring shaped shell 29 of the cope. This cylindrical sleeve extends from the upper end of the cope to a little more than one-half of the length of the cope, and a slot 32 is cut vertically through one side of its entire length to allow it to expand freely, and at the opposite or bottom end of the cope a chill ring portion 33 is secured.

The ring 29 is formed with oppositely positioned lugs 34 having bolt apertures, and the chill ring 33 is formed with similar apertured lugs 35, which are adapted to register with the lugs 34, and bolts 35^A are passed through these lugs and secure the rings 29 and 33 together. The inner face of the ring 33 is machine finished, and its lower edge is recessed, as shown at 36, to match a recess 37 made by pattern part 6 in the other half of the mold, which together form the outline of the flange of the wheel.

The upper edge of the cope shell is provided with a horizontally arranged flange 38, and the lower end of the chill ring is machine finished and turned to fit against the inside surfaces of the lugs 22 and 9^A respectively, when this cope is placed upon either the master pattern or the nowel ring.

It is necessary to lower the cope on the master pattern in order to mold the hub and arrange the upper part of the cope to match the mold of the lower part. Consequently, having set and leveled the master pattern in a position where a molder can work around it, the cope is raised by hand if it is small and light or by a chain hoist if it is too heavy, the opposite sides of the cope being provided with trunnions 39 or handles by which the cope may be handled. These trunnions are positioned to permit the cope to be turned over upside down when suspended by chains, so as to bring the lower edge of the chill ring and of the cope uppermost and the top end of the cope down. This permits the molder to work off and otherwise dress the side and end surfaces of the chill ring and to clean off the lower edge of the cope so that it will rest down tightly on the top plate of the master pattern. The molder, having cleaned these surfaces, turns the cope again right side up and then lowers it over the master pattern and down onto its top plate between its lugs 22, between which it fits with a bearing fit which centers the cap accurately and concentrically on the master pattern. The molder then places

the hub pattern 27^A down through the cylindrical sleeve onto the center of the master pattern, providing he did not do so before placing the cope on the master pattern, and then sets a core 40 on the hub 70 pattern, which core is of slightly greater diameter than the hub pattern and of a thickness to extend to the top of the ring 29, and having done this he fills and tamps the cylindrical sleeve with sand even to the 75 top of the core 40, and also fills and tamps the spaces with sand between the outside of the cylindrical sleeve and the ring 29.

The core comprises a circular block of sand baked as is usual in forming cores for 80 molding, and this block is provided with a plurality of apertures 41, which are of a size to allow liquid iron to flow readily through them. A pouring guide ring 42 is then placed on the plate and the cope is 85 filled with sand and tamped even with its top edge in the usual molding manner.

The disk portion of the master pattern is arranged to extend to and close enough against the inner side surface of the chill 90 ring of the cope so that when the top of the cope is filled with sand it cannot flow between the side of the disk and the side wall of the chill ring.

The diameter of the chill ring is of a 95 size to form the tread surface of the wheel when cast, and it is arranged to form the tread and flange portions of the wheel to be cast of the desired thickness when placed on the lower part of the mold that is held 100 by the drag ring where it is arranged in such relative relation to the wall of the lower mold as to allow of tread and flange portion of a wheel of the desired thickness to be cast, as will be more fully described 105 hereinafter. The cope is then raised up from the master pattern and turned upside down again and the hub pattern which lifts from the master pattern with it is removed 110 from it, leaving the mold of the hub in the cope. The side and end surfaces and lower edge of the cope are again cleaned and the cope or upper section of the flask is ready to be lowered onto the lower section, 115 which is molded in the drag or nowel ring.

Before lowering the cope upon the nowel ring, which holds the other part of the mold, a core 43 which is adapted to form the bore of the hub is placed centrally in the hub opening 12 of the first half of the mold 120 and rests in a recess 44 formed by a projection 45 on the hub pattern 3, as shown in Fig. 2. This core extends above the mold and has a centering pin or projection adapted to enter a centering aperture in the block 40, as shown in Fig. 6. This core is given a true vertical position by means of a gage stick 47, as shown in Fig. 1, the said gage corresponding in length to the distance between the inner face of any one of the cen- 125 130 135

tering lugs 9^a and the periphery of the said core, when the same is in a true vertical position. By placing this gage successively between each of the centering lugs and the core, the core is thereby given a true vertical position.

The inside diameter of the lugs of the master pattern and of the drag ring are of exactly the same size. Consequently, the 10 lower end of the chill ring of the cope fits in bearing contact with the inside surface of the lugs of the drag ring and down against its turned flat top surface 9, and the cope is accurately centered by means 15 of the concentrically bored lugs and the machined surfaces of the drag ring and of the cope, and the master pattern has arranged the mold of the hub and the bottom of the mold of the cope so that it fits on and is 20 centered accurately on the mold of the lower half or drag ring part of the mold. The cope and drag ring are then clamped by the hooked dog rods 16 by wedges, and the flask and mold is ready to pour, which is done by 25 pouring the hot metal in the guide pouring ring onto the core block 40, from which the hot metal flows through the apertures 41 in this block into the hub space in the mold and into the spoke spaces and into the circumferential space between the wall of the 30 lower section of the mold and the side and end surfaces of the chill ring of the cope or upper section of the mold, which it fills and forms the tread and flange portion of the 35 wheel, thus completing the molding of a wheel that is accurately round and perfectly formed in all of its parts.

I have found in practice that in using a cope having the chill ring cast integral with 40 the hub molding portion of the cope that the great heat to which the chill ring is subjected by the contact of the hot metal directly with it at each cast causes it to commence to check soon after a new ring 45 cope is used, and this checking develops into cracks with roughened up edge portions that develop into an open crack and rupture of the ring and necessitates the throwing away of the cope and the replacing of it by an 50 entirely new one. This is expensive, as the new cope and its chill ring have to be machine finished and accurately fitted to the lugs of the master pattern and of the drag ring, and my present invention contemplates a 55 cope divided into two detachably connected parts, the top part of which is made of a length to carry the whole of the cylindrical hub receiving sleeve and its spokes, and the other is made of a length to carry the whole 60 of the chill ring portion of the cope. These two separately made parts of my invention may be secured together by any suitable means for detachably connecting them together. I preferably carry out this feature of my invention by casting the radially

projecting lug portions 34 and 35 at equidistances apart around the meeting edges of the two parts and machine finish their meeting surfaces, as well as the surfaces of the meeting edges of the two parts of the cope, and rigidly bolt these two parts together and then machine finish the chill ring and the lower and peripheral edges of the chill ring part of the cope after these parts are securely bolted together. Then when a ring is worn out it can be removed from the top part of the cope and a new chill ring part can be attached to the top part of the cope, as the top part of the cope will last until accidentally broken. This feature of my invention effects a great saving in the cost of keeping up these specially constructed and arranged flasks.

The commonly used iron flask is provided with ears on the drag part containing a perforation and an ear on the cope part provided with a round pin. The pins and holes soon wear loose and leave a loose connection between the two parts of the flask, as their meeting edges are narrow and unfinished and provide a flask wholly inserted to the molding of wheels of accurate size and form in large number, and with such a flask it would be impossible for two different workmen to prepare the molds so that they would go quickly together in such accurate relation as to mold wheels of the same size. My flask, on the other hand, can be handled roughly and quickly in putting in all of these operations of molding and putting together, and their parts always come accurately to a common center.

My invention is simple but permits any desired number of any size or shape to be made by making a drag ring, a master pattern, and a cope embodying the features of my invention, and the most valuable feature in connection with my improved flask is that it permits of one molder in one part of a foundry to make up any desired number of the lower or drag ring parts of the mold and another molder to mold up from the master pattern the same number of the upper parts of the pattern in the cope with the assurance that the parts thus separately made up by different molders will fit accurately and concentrically together.

Another feature of my invention of value is that when it is desired to cast the hub with an axial aperture through it, the core 43 can be accurately centered from the four machine bored lugs of the drag ring by the gage stick 47 or by a rule, by applying it successively to the opposite lugs and moving the core until it stands in the center of 12 the hub aperture of the mold.

My invention is simple and a great labor saver in the continuous production of cast car or other wheels in large numbers of accurate form and size, and, while I have 13

illustrated the preferred construction and arrangement of it, various changes might be made without departing from the spirit of my invention.

5 Having described my invention, what I claim as new and desire to secure by Letters Patent is:

1. A flask comprising upper and lower mold-sections, and upwardly projecting portions on said lower section having tapered inner faces with which said upper section engages and by means of which said sections are maintained in proper relation.

10 2. A flask comprising upper and lower mold-sections, a chill-plate between said mold-sections, and upwardly projecting portions on said lower section having tapered inner faces with which said upper section and said chill-plate engage and by 20 means of which the parts are maintained in proper relation.

15 3. A flask comprising upper and lower mold-sections, a divided sleeve within said upper section, radial arms connecting the wall of said upper section and said sleeve, and projecting portions on said lower section for maintaining said sections in proper relation.

25 4. A flask comprising upper and lower mold-sections, a chill-plate detachably secured to said upper section, and upwardly projecting portions on said lower section having tapered inner faces with which said upper section and said chill-plate engage and by means of which the parts are maintained in proper relation.

30 5. A cope comprising a ring having detachably secured thereto a chill-ring, the peripheral portions of said rings being of the same diameter.

35 6. A flask comprising a lower section having upwardly projecting portions with tapered inner faces, and an upper section or

40 cope comprising a ring having detachably secured thereto a chill-ring, the peripheral portion of said rings being of the same diameter and adapted to engage the inner faces of the projecting portions of the lower section.

45 7. A car-wheel mold having a lower section comprising an outer ring having upwardly projecting portions with tapered inner faces and containing sand molded to form the spokes and portions of the rim, flange, and hub; and a separate upper section, comprising an outer ring having detachably secured thereto a chill-ring, seated within the upwardly projecting portions of the lower section, said upper section having sand molded therein with surfaces coöperating with those of the upper section to complete the wheel.

50 8. A flask comprising a drag-ring, upwardly projecting portions on said drag-ring having tapered inner faces and providing with said drag-ring an annular shoulder, and a separate upper section having a chill-ring detachably secured thereto, 55 and adapted to seat on said shoulder.

55 9. A flask comprising a drag-ring, upwardly projecting portions on said drag-ring having tapered inner faces and providing with said drag-ring an annular shoulder, and a cope comprising a ring having a chill-ring detachably secured thereto, 70 the peripheral portions of said cope and chill-rings being of the same diameter, said chill-ring being adapted to seat on said annular shoulder.

75 In testimony whereof I affix my signature in presence of two witnesses.

ALFRED CORDINGLY.
